PLOW BEAM EXTENSION

CROSS-REFERENCE TO RELATED APPLICATION

This application is a division of my copending application Ser. No. 487,730 filed Sept. 16, 1965, now U.S. Pat. No. 3,351,138.

BACKGROUND OF THE INVENTION

The present invention relates generally to improvements in trip mechanisms for earth-working tools, such as breakback plows.

Attempts to prevent damage to earth-working tools, such as plows bottoms, caused by the tool striking an earthbound obstruction, date from almost the inception of man's tillage of the soil. Efforts to cushion or reduce impact load imposed on tillage equipment have continued up to the present time. However, even recent solutions to this problem are, or may be rendered obsolete by subsequent improvements in tractor speed and horsepower. Consequently, each improvement in tractors almost inherently necessitates further search for more effective solutions to prevent impact damage to earth-working tools caused by obstructions hidden in the soil.

The primary object of the present invention is to provide a laminated plow beam extension joint which affords optimum resistance to both bending moment and shear stresses during plowing.

This and other objects and features of the present invention will become more fully apparent from the following description and appended claims taken in conjunction with the accompanying drawings wherein:

FIG. 1 is a side elevation of one embodiment of the present invention equipped with an eccentric column of fixed eccentricity;

FIG. 1a is a schematic diagram of the column of FIG. 1;

FIG. 2 is a rear elevation taken along line 2-2 of FIG. 1;

FIGS. 3, 4 and 5 are cross-sectional views taken respectively along lines 3-3, 4-4, and 5-5 of FIG. 1; and FIG. 6 is a fragmentary top view of FIG. 1.

Referring to the drawings wherein like numerals are used to designate like parts throughout, FIG. 1 shows one form of trip mechanism of the present invention, generally designated 10, in its normal operating position on a breakback plow. Trip mechanism 10 is interposed between a substantially horizontally extending rigid plow support, generally designated 12, and a plow standard 14 to which a plow bottom 16 is rigidly attached, as for example, by bolts.

The rigid support 12 comprises a plow beam 17 and a forged plow beam extension 18. The plow beam extension 18, as best illustrated in FIGS. 1, 3, 4 and 5, is rigidly joined to the plow beam 17 by a laminated connection 19 to afford optimum, unitary resistance to the bending moment stresses, the shear stresses, and the torsional stresses transmitted thereto by action of the plow against the soil.

Plow beam extension 18 has a central body 22 at its forward end from which upper and lower integral flanges 23, and 24, respectively, project essentially horizontally toward the plow beam 17. The flanges 23 and 24 respectively engage the upper surface 26, lower surface 28 and the side surface 30 of the plow beam 17 at angular recesses 32 and 34 of the plow beam extension 18, as depicted in FIGS. 3 and 4. By the action of the flanges 23 and 24 of the beam extension 18 against the beam 17, relative pivotal movement of the plow beam 17 with respect to the plow beam extension 18 is effectively prohibited and, thus, the previously-mentioned bending moment stresses are unitarily resisted by the plow beam 17 and the plow beam extension 18.

It is to be observed that the central body 22 of the plow beam extension 18 is progressively divergently tapered from front to rear such that the body 22 is narrower (and of less cross-sectional area) at the location of the line 3-3 of FIG. 1 than at the location of line 4-4, and reaches a maximum width (and area) at the location of line 5-5, where the flanges 23 and 24 cease to exist as the plow beam extension consists solely of the enlarged central body 22.

The plow beam extension 18 may be appropriately bossed adjacent an aperture (not visible) through which the major pivot bolt 36 passes as well as adjacent other bolt receiving apertures and has a downwardly and rearwardly open side recess or socket 38 disposed at the upper portion of a rear reinforcing rib 40. The specific function of the recess 38 will be described subsequently.

The vertically extending legs 43 and 45 of a pair of "L-shaped" brackets 42 and 44, preferably fabricated from angle iron, respectively abut the plow beam 17 on one side at surface 46 and the plow beam extension 18 on the opposite side at surface 48 at the laminated connection 19. This prevents relative lateral sway movement between the plow beam and the plow beam extension in response to the previously-mentioned torsional stresses.

The upper surface 50 and 52 of the generally horizontally extending legs 54 and 56 of the respective brackets 42 and 44 are adapted to receive a tool or stiffener bar (not shown) where a gang of plow bottoms are to be simultaneously drawn by a tractor.

A plurality of nut and bolt assemblies 20, 21 are used to hold the brackets 42 and 44, the rearward end of plow beam 17 and the forward end of the plow beam extension 18 as an integrated unit.

Plow beam extension 18 is rigid relative to the beam 17 and does not move relative to the beam 17 during release or tripping of the plow bottom 16 and the standard 14 from the working position (shown in solid lines in FIG. 1) and to the idle position (shown fragmentarily in phantom lines 60 in FIG. 1).

A pair of vertically extending parallel gusset side plates 70 and 72 are pivotally connected to the plow beam extension 18 at the major pivot bolt or pin 36, which pin passes through aligned apertures in each plate. The gusset plates 70 and 72 are literally spaced from each other as depicted in FIG. 2. The plates 70 and 72, which may be characterized as rotatable means (along with all structure carried by the gusset plates), are designed to rotate counterclockwise as shown in FIG. 1, about the pivot bolt 36 when the plow bottom 16 is displaced from its ground-working position toward its idle position, as for example when the plow bottom strikes a substantially immovable earthbound obstacle.

Additionally, the gusset plates 70 and 72 are rigidly fastened to the standard 14 by means of bolts 74 and 76 (FIG. 1). Consequently, there is never any appreciable relative movement between the gusset plates 70 and 72 and the standard 14 or the plow bottom 16 during the previously-mentioned displacement toward the idle position.

The release mechanism 10 broadly includes a pair of external side latch links 80 and 82, a detent roller 84, a stop pin 86 carried by the gusset plates 70 and 72 within the space between the gusset plates, and an eccentric leaf spring column 90.

The two side latch links 80 and 82, are respectively positioned adjacent the exterior surfaces of the gusset plates 70 and 72, suitable spaces being provided therebetween, if desired. Latch links 80 and 82 are joined together by a bolt 94 and are also coupled by bolt 100 which rotatably supports detent roller 84 between links 80 and 82. The bolt 94 passes through an aperture 96 (FIG. 2) in each side link 80 and 82 independently of the gusset plates 70 and 72. A pin 92 passes through a vertically elongate slot 98 in each side link 80 and 82 and also through a bore 99 in each gusset plate 70 and 72. Links 80 and 82 are pivotally supported upon plates 70, 72 by pin 92 and can shift in translation relative to plates 70, 72 by the amount permitted by slots 98.

Slots 98 accommodate limited relative upward translation of gusset plates 70 and 72 with respect to links 80 and 82 during the initial displacement of the plow toward its idle position.

The detent roller 84 is carried by bolt 100 which passes through an aperture 101 (FIG. 2) in each latch link 80 and 82 as well as through a central bore in the detent roller 84, to rotatably carry the roller upon the shank of the bolt.

As best seen in FIG. 2, roller 84 has a central cylindrical portion 102 of comparatively large diameter which is normally seated in socket recess 38 of beam extension 18 when the plow bottom is in its plowing position, as shown in FIG. 1. The enlarged portion 102 is integrally flanked on each side by cylindrical portions 104 of smaller diameter. The smaller diameter of the portion 102 provides adequate clearance between the roller 84 and a clearance recess 106 in each of the gusset plates 70 and 72.

Detent roller 84 is normally constrained in the illustrated position of FIG. 1 by a relatch spring 108, the ends of which are respectively secured at a block 110 and a pin 112 to tension relatch spring 108. The block 110 is integrally secured to the gusset plate 70, as by welding, and has an aperture (not shown) therein through which a short rod 114 passes. The rearward end of the rod 114 is equipped with an aperture (not visible) through which the adjacent end 115 of the spring 108 passes in the manner shown in FIG. 1. The forward end of the rod 114 is threaded at 116 to receive a nut 118 and a lock nut 120.

The relatch pin 112 is integrally secured to the latch link 80, as by welding, to retain the end 122 of the spring in the illustrated position. Thus, the relatch spring 108, which is preferably of relatively low spring rate, tends to retain detent roller 84 in the socket 38. The spring 108 also tends to return the roller 84 to its abutting position against the recess 38, as shown in FIG. 1, when the plow is being reset after being tripped to the idle position.

Eccentric column 90 comprises a vertically disposed, laterally deflectable leaf spring 130 of substantial unsupported length which is preferably fabricated from suitable high strength steel.

Eccentric column 90 is secured in the illustrated position of FIG. 1 by a lower eye 136 and an upper eye 138, both integral with the leaf spring 130, which are respectively rotatably carried upon pin 92 and bolt 94. Suitable spacers may be used to separate the eyes 136 and 138 from the inside surfaces of the gusset plates 70 and 72. The leaf spring 130 is eccentrically offset from the axis 140 (passing between the centers of the bolts 92 and 94) by a selected eccentricity 142.

During no-load conditions, the central portion of the leaf spring 130 will be spaced a desired, predetermined distance 132 from the rear surface of the stop 86. During normal plowing operations, variations in draft applied to the plow oscillate gusset plates 70, 72 and cause leaf spring 130 to resiliently flex or buckle within the space 132, as pin 92 moves in slot 98 in response to oscillation of the plow.

If the plow bottom 16 strikes an essentially immovable obstacle, gusset plates 70, 72 pivot about the bolt 36 and pin 92 moves upwardly in the slot 98 to flex the spring 130 into contact with the stop pin 86. Further flexing of spring 130 after its central portion engages pin 86 biases the upper end of links 80, 82 in clockwise pivotal movement about pin 92, thereby resiliently biasing roller 84 out of recess 38 on plow beam extension 18.

Roller 84 is released from recess 38 by the biasing force applied by spring 130, and this biasing force comes into action only after spring 130 has been bowed enough to contact pin 86. When the central portion of spring 130 cannot move any further toward the left, as viewed in FIGS. 1 and 1a, the upper end of the spring must move to the right upon further upward movement of pin 92.

The geometrical relationship of pivot 36, pin 92, roller 84, and recess 38 is such that the normal forces applied by an overload to the plow tend to seat roller 84 more firmly in recess 38—i.e. an overcenter relationship exists when roller 84 is seated. The overcenter relationship is overcome by causing the overload forces to “squeeze” the opposite ends of spring 130 toward each other, thereby bowing the spring. The length of slot 98 and the initial spacing 132 between the spring and pin 86 are so related that the compressing of the ends of spring 130 upon the movement of pin 92 from its normal position to the upper end of slot 98 causes a bowed deflection of the central portion of the spring greater than spacing 132. After roller 84 moves out of recess 38, the plow bottom 16, the release mechanism 10 and the gusset plates 70 and 72 can pivot about the major pivot bolt 36 into the elevated idle position. Once the detent roller 84 is ejected from the socket 38, the leaf spring 130 will straighten out and the bolt 92 will return to a position adjacent the bottom of the slot 98.

Once the obstacle has been cleared, the plow bottom 16 is reset or returned to its working position automatically either by (1) raising the entire plowing implement causing the release mechanism to return by force of its own weight to its working position, or (2) reversing the implement direction of movement to pull the plow bottom back into its working position by reason of contact with the ground, as, for example, when using larger plows where the entire implement may not be conveniently raised.

The invention may be embodied in other specific forms without departing from the spirit or essential characteristics thereof. The present embodiments are therefore to be considered in all respects as illustrative and not restrictive.

I claim:

1. In a plow having a main beam, a plow standard and means connecting said plow standard to said main beam, the improvement of said means including a plow beam extension having a body progressively increasing in width and cross-sectional area from the plow beam toward the plow standard, spaced upper and lower flanges extending laterally of said body and engaging upper and lower surfaces of said main plow beam for resisting bending movement stresses, means securing said plow beam extension to said plow beam against relative fore and aft movement to accommodate an essentially unitary resistance to said shear stresses, and means mounted on said securing means having horizontally disposed and outwardly projecting flanges for resisting lateral swaying movement between the main beam and the plow beam extension in response to torsional stresses.
